SOUNDING TRUNDLING TOY

Filed Sept. 1, 1934

UNITED STATES PATENT OFFICE

1,985,117

SOUNDING TRUNDLING TOY

Jasper Tirrito, Chicago, Ill.

Application September 1, 1934, Serial No. 742,481

4 Claims. (Cl. 46—45)

This invention relates to certain new and useful improvements in sounding trundling toys.

The primary object of the invention is to provide a toy of the foregoing character wherein a figure toy symbolical of a clown or other character is mounted on a wheeled carriage with the arms thereof operatively engaged with the crank portion of the shaft that supports the carriage wheels with a cymbal carried by each hand to be moved into contact with cymbals carried by the wheeled carriage, the cymbals to be sounded during trundling of the carriage.

A further object of the invention is to provide a sounding trundling toy of the foregoing character wherein the crank portion of the wheel supporting shaft of the carriage is adjustable to vary the length of throw of the arms of the figure toy with the cymbals carried by the carriage embodying spring supports to compensate for a variance in the length of throw of the arms.

With the above and other objects in view that will become apparent as the nature of the invention is better understood, the same consists in the novel form, combination and arrangement of parts hereinafter more fully described, shown in the accompanying drawing and claimed.

In the drawing:

Figure 1 is a side elevational view of a sounding trundling toy constructed in accordance with the present invention;

Figure 2 is a top plan view of the toy with the head and garment of the toy figure removed to show the pivotal mounting for the arms of the toy figure;

Figure 3 is an enlarged side elevational view, partly broken away and shown in section with the garment of the toy figure removed and illustrating the spring mounting for the cymbals carried by the wheeled carriage;

Figure 4 is a vertical cross-sectional view taken on line 4—4 of Figure 3, showing the adjustable crank portion of the shaft that supports the carriage wheels and operates the arms of the toy figure; and

Figure 5 is a detail sectional view showing the crank portion of the wheel carrying the shaft in its adjusted or extended position.

Referring more in detail to the accompanying drawing, the sounding trundling toy embodies a carriage constructed in any preferred manner and of an appropriate shape or design, the same being illustrated as rectangular in form and embodying side walls 10, end walls 11 and a top wall 12, the carriage being open at its bottom

or lower end as shown in Figure 4. A two-part axle comprising axle sections 13 has the sections journaled at their outer ends with the side walls 10 of the carriage and projecting outwardly thereof to provide supports for the ground wheels 14, the outer terminal ends 15 of the axle sections 13 being reversely bent into engagement with the adjacent wheel for locking the wheels to the shaft section. The carriage is provided with a handle bar structure 16 to effect trundling thereof.

The crank element is located at the inner adjacent ends of the axle sections 13, being designated in general by the reference character 17 and including the formation of angle ends 18 on the axle sections 13 that are received in socketed legs 19 of a crank arm 20. The angle ends 18 of the axle sections 13 are adjustably retained in the socketed legs 19 by means of the set screws 21 threaded through the sides of said legs and engaged with said angle ends as illustrated in Figures 4 and 5.

A figure toy 22 is mounted upon the wheeled carriage and as shown in Figure 3 includes a post 23 rising from one end of the top wall 12 of the carriage with the upper end thereof tapered as at 24 to receive a socketed head 25

of a figure toy, this arrangement permitting the substitution of figure toys of any desired character. A rod 26 is journaled transversely of the post 23 and is provided with angle ends 27 to which are attached arms 28 to represent the arms of the figure toy 22. Each arm 28 is provided with a hand 29 that has a cymbal 30 attached thereto. The post 23 and arms 28 of the figure toy 22 are covered by a garment 31 and create the impression of a figure toy seated within the carriage.

Cymbals are carried by the carriage for cooperation with the cymbals 30 carried by the arms 28 and as shown in Figures 3 and 4 include a bar 32 extending transversely of the carriage between the side walls 10 thereof adjacent the top wall 12, the bar 32 having a pair of coil springs 33 anchored at their lower ends thereto and respectively extending upwardly through openings 34 in the top wall 12 and each supporting a cymbal at its upper end in line with and to be contacted by cymbals carried by the arms 28.

The operating means for the arms 28 carrying the cymbals 30 includes a cross rod 36 connecting the arms 28 as shown in Figures 2 and 4 with a pitman rod 37 having an eye 38 at one end inclosing the rod 36 intermediate its

ends and an eye 39 at its other end surrounding the crank arm 20 of the axle sections 13, the pitman rod 37 extending through a slotted opening in the top wall 12 of the carriage.

5 With the crank arm 20 in the position illustrated in Figures 3 and 4, trundling movement of the carriage effects rotation of the sections 13 and crank arm 20 for reciprocating the pitman rod 37 to raise and lower the arms 28 on their pivot rod 26, the cymbals 30 being raised and lowered with the arms 28 for engaging the cymbals 35 supported by the spring members upon the bar 32. The length of throw of the arms 28 may be varied by adjusting the crank arm 20 by means of socketed legs 19 on the angle ends 18 of the axle section 13 to compensate for the difference in length of throw of the arms 28, the cymbals 35 are mounted upon the springs 33 that are compressed during downward movement of the arm carrying cymbals 30 into contact with the cymbals 35.

10 From the above detailed description of the invention, it is believed that the construction and operation thereof will at once be apparent and 15 while there is herein shown and described the preferred embodiment of the invention it is nevertheless to be understood that minor changes may be made therein without departing from the spirit and scope of the invention as claimed.

20 30 I claim:—

1. In a sounding trundling toy, a carriage, a two-part axle journalled in the carriage with a ground wheel fixed to each end thereof, a crank arm adjustably connected to the adjacent ends 35 of the axle sections, a pair of cymbals resiliently supported on the carriage, a figure toy seated on the carriage, and including a pair of pivoted arms, a cymbal carried by each arm and a pitman rod connection between the crank arm 40 of the axle and the arms of the figure toy.
2. In a sounding trundling toy, a carriage, a two-part axle journalled in the carriage with a ground wheel fixed to each end thereof, a crank

5 arm adjustably connected to the adjacent ends of the axle sections, a pair of cymbals resiliently supported on the carriage, a figure toy seated on the carriage, and including a pair of pivoted arms, a cymbal carried by each arm and a pitman rod connection between the crank arm of the axle and the arms of the figure toy, the resilient support for the cymbals on the carriage including a cross bar in the carriage and coil springs carried by the cross bar for the support of the cymbals. 10

3. In a sounding trundling toy, a carriage, an axle journalled in the carriage with a ground wheel fixed to each end thereof, an adjustable crank arm in the axle, a pair of cymbals on the carriage, a figure toy on the carriage including a pair of pivoted arms, a cymbal on each arm 15 cooperating with the cymbals in the carriage, a pitman rod connection between the crank arm and the pivoted arms of the figure toy, said 20 crank arm being adjustable to vary the length of throw of the arms and spring mountings for the cymbals on the carriage to compensate for adjustments of the crank arm.

4. In a sounding trundling toy, a carriage, an axle journalled in the carriage with a ground wheel fixed to each end thereof, an adjustable crank arm in the axle, a pair of cymbals on the carriage, a figure toy on the carriage including a pair of pivoted arms, a cymbal on each arm 30 35 cooperating with the cymbals in the carriage, a pitman rod connection between the crank arm and the pivoted arms of the figure toy, said crank arm being adjustable to vary the length of throw of the arms and spring mountings for the cymbals on the carriage to compensate for 40 adjustments of the crank arm, the axle being formed of two sections with adjacent ends bent at right angles, and the crank arm having socketed legs in which the angle ends of the axle sections are respectively adjustably recessed.

JASPER TIRRITO.
